PULLEY HOUSING

Application filed January 30, 1930. Serial No. 424,620.

This invention relates to improvements in pulley housings.

One of the objects of our invention is the provision of a pulley housing which is particularly adapted to that class of pulleys supported in window frames and over which the sash cord passes for supporting the sash weight and window, wherein the pulley housing, the attaching plate and the guides for the sash cord are formed of a single piece of material.

Another object of our invention is the provision of an improved housing for sash pulleys wherein the housing and component parts are formed of a single piece of material in order to provide for a more rigid and simple construction and for the purpose of reducing the manufacturing cost of this article, so that it can be placed on the market and sold at a very small cost.

A further object of our invention is the provision of a pulley housing of the above character formed of a single piece of material and wherein laterally disposed ribs are formed in the construction of the housing adapted to snugly fit the mortise within the window frame so as to prevent lateral movement on the part of the pulley housing, while the sash cord is passing over the pulley, thus retaining the housing in its respective position so that the sash cord will be maintained in direct alignment at all times.

A still further object of our invention is the provision of a pulley housing formed of a single piece of material, wherein the guiding hoods which direct the sash cord over the pulley are formed integral with the housing and are so positioned as to permit the cord to be quickly and easily passed around the pulley.

With the above and other objects in view, the invention consists in the novel features of construction, the combination and arrangement of parts hereinafter more fully set forth, pointed out in the claim and shown in the accompanying drawings wherein:

Figure 1 is a vertical sectional view, taken through a window frame, illustrating the application of my improved pulley housing, with the housing disclosed in side elevation;

Figure 2 is a sectional view on the line 2—2 of Figure 1;

Figure 3 is a transverse section on the line 3—3 of Figure 1;

Figure 4 is a bottom plan view of a pulley housing; and,

Figure 5 is a plan view of the blank from which the housing is formed.

In the general construction of window frames, there is provided a longitudinal passage 1, within the main portion of the frame 2, and this passage is closed by means of a cover board 3. Usually, in placing these sash pulleys within the frame, a mortise is cut through the cover plate 3 and the pulley housing mounted in the frame, and due to the fact that in cutting these openings, they are generally made a little bit larger than the pulley housing, and when the pulley is placed in position, it has a tendency toward lateral movement when the sash cord is passing over the pulley, and furthermore, with the usual construction of pulley housings, it is rather difficult to thread the cord over the pulley unless suitable guiding means is provided.

In the general construction of our improved one-piece housing, it will be noted that the blank is stamped out in the form illustrated in Figure 5, and the central portion of the blade having its ends extended to form the attaching means for the housing when completed. One edge of the blank is provided with straight longitudinal portions 1' at each side of the longitudinal center which terminates in a tab 2' and directly below this tab is another longitudinal portion 3' with a portion of the blank slit inwardly, as shown at 4 at the inner edge of the longitudinal portion 3'.

The edge opposite the longitudinal portion 1' of the blank is formed rounding at the ends, as shown at 5, the purpose for which will hereinafter be more fully set forth. In forming the main portion of the housing, the side portions 6 and 6' of the blank are bent at right angles to the central portion 7 which forms the attaching plate on the line 8 and adjacent the attaching plate each side portion of the blank is folded upon itself to form the hollow rib 9 which is adapted to fit snugly

within the mortise 10 in the cover board 3. If found desirable, these hollow ribs 9 may be formed with an inclined outer wall, as illustrated in Figure 3, so that a substantially driving fit may be had when placing the pulley 15 in the housing, as shown in Figure 3.

The outer ends of the sections or side portions 6 and 6' are arcuately curved as well as the edge opposite the longitudinal edge 1' to form guides for the rope which passes over the pulley within the housing, the tabs 2' being pressed inwardly, as shown at Figure 1, to assist in guiding the rope over the pulley.

The ends and one side edge of each of the sections 6 and 6' are arranged in abutting relation, as shown in Figures 3 and 4, and form the side walls for the housing, as well as one edge and one end, while the part adjacent the longitudinal portion 1' is bent inwardly on the line 11 to form opposite end walls of the housing, thus leaving the ends of the central portion or face plate extending beyond both ends of the housing and these ends are provided with perforations 12 to receive screws 13 which engage within the cover board 3 for retaining the housing in position within the mortise 10.

In order to provide a suitable guide for the sash cord upon the exterior of the cover board, the central portion of the main blank which constitutes the face plate is provided with an opening adjacent one end of the face plate and a portion of the material is drawn out from the face plate to form the nose piece 14, the side walls of which continue outwardly from one side of the hollow rib 9, as shown. The outline of the nose 14 tapers toward the closed end thereof, as shown in Figure 1, so as to cooperate with one end of the housing to provide a properly formed guide for the sash cord when extended around the pulley.

The pulley 15 in the present instance is mounted upon a transverse pin 16 which is normally provided with a head on one end and in securing the pulley in position, the smooth end is inserted through the openings 17 in the side walls of the housing and through the pulley and the other end is then riveted, spun or enlarged in order to retain the pin in position and securely hold the two side walls of the housing against outward movement.

The above construction provides a complete housing for a pulley, the housing being formed of a single piece of material and stamped to form the outer line, as shown at Figure 5 and then quickly bent into shape to provide the complete housing as shown more clearly in Figures 1 and 4. In placing the pulley within the housing, it can be inserted therein at one end before the longitudinal edges 1' are bent over into abutting relation.

It will be noted that by providing the housing with a substantially hollow outstanding rib 9, as illustrated, this rib will completely

fill the mortise 10 and prevents any lateral movement on the part of the housing, while the sash cord is being passed therethrough over the pulley 15 and this tight fitting of the rib within the mortise will assist in retaining the housing within the mortise. One of the essential features of our improved pulley housing is the fact that the entire housing, including the attaching plate 7 and the cord guides are formed of a single piece of material.

It will be apparent that a pulley housing constructed in accordance with the above, will not only reduce the cost of manufacturing the pulley housings of this character, but the features incorporated in the forming of the housing are greater and greatly facilitate not only the mounting of the pulley housing, but the guiding of the sash cord or chain through the housing and over the pulley, and it is believed that a pulley housing constructed in accordance with the above will be far superior to any known pulley housings on the market at the present time.

While we have shown and described the preferred embodiment of our invention, it will be apparent that slight changes may be made in the construction when putting the invention into practice without departing from the spirit of the same or the scope of the appended claim.

We claim:

A one-piece housing of the class described including a hollow body, an arcuate guide portion leading from one end of the body, an attaching plate at one side of the body, an arcuate nose piece integral with the attaching plate and laterally disposed ribs on the body adjacent the attaching plate.

In testimony that we claim the foregoing we have hereunto set our hands at Milwaukee, in the county of Milwaukee and State of Wisconsin.

JAMES H. REMINGTON.
JOHN D. REMINGTON.
VOLNEY G. GRAHN.
